CONDITION RESPONSIVE DEVICE

Walter E. Edelman, Minneapolis, Minn., assignor to Honeywell Inc., Minneapolis, Minn., a corporation of Delaware

Filed July 2, 1969, Ser. No. 18,028

Term of patent 14 years

Int. Cl. D10—09

U.S. Cl. D52—7

FIG. 1

FIG. 2

FIG. 4

FIG. 3

FIG. 1 is a front view of a condition responsive device embodying the new design;

FIG. 2 is a top view of the device, the bottom view being substantially a mirror image thereof;

FIG. 3 is a side view of the device, the opposite side view being substantially a mirror image thereof; and

FIG. 4 is a top plan view with portions fragmentarily shown in cross section along line 4—4 of FIG. 1.

I claim:

The ornamental design for a condition responsive device, substantially as shown and described.
